United States Patent Office

Des. 205,484
Patented August 9, 1966

205,484

BOAT

Paul A. Lindh, 42 Bateman Ave., Newport, R.I.

Filed Feb. 8, 1965, Ser. No. 83,736

Term of patent 14 years

(Cl. D71—1)

FIG. 1

FIG. 2

FIG. 3

FIG. 4

FIG. 5

FIG. 6

FIG. 7

FIG. 1 is a perspective view of a boat showing my new design;

FIG. 2 is a side elevational view thereof;

FIG. 3 is a bottom plane view thereof;

FIG. 4 is a front elevational view thereof; and

FIG. 5 is a rear elevational view thereof.

FIG. 6 is a cross sectional view taken on the line 6—6 of FIG. 2.

FIG. 7 is a cross sectional view taken on the line 7—7 of FIG. 2.

The dominant features of my design reside in the full-line portions of the drawing.

I claim:

The ornamental design for a boat, substantially as shown and described.
